SLIPPER

Ray E. Larsh, Milwaukee, and Donald I. Urbansky, Thiensville, Wis., assignors to Kleen Test Products, Inc., Milwaukee, Wis.

Filed Oct. 26, 1971, Ser. No. 192,169

Term of patent 14 years

Int. Cl. D2—04

U.S. Cl. D2—301

FIG. 1 is a side perspective view of a slipper showing our new design in wearing position;

FIG. 2 is a side elevational view thereof;

FIG. 3 is a top plan view when in non-wearing position; and

FIG. 4 is a bottom plan view.

We claim:

The ornamental design for a slipper, substantially as shown and described.
